UNITED STATES PATENT OFFICE.

WILLIAM J. P. MOORE, OF NEW YORK, N. Y.

DESIGN FOR A CHASSIS FOR AUTOMOBILES AND OTHER VEHICLES.

54,443.

Specification for Design.

Patented Feb. 10, 1920.

Application filed January 15, 1917. Serial No. 142,572. Term of patent 3½ years.

To all whom it may concern:

Be it known that I, WILLIAM J. P. MOORE, a citizen of the United States, and resident of New York, in the county of New York and State of New York, have invented a new, original, and ornamental Design for a Chassis for Automobiles and other Vehicles, of which the following is a specification, reference being had therein to the accompanying drawing.

Figure 1 is a top plan view of a chassis

for automobiles and other vehicles showing my new design.

Fig. 2 is a side elevation of the same.

Fig. 3 is a front elevation.

I claim:

The ornamental design for a chassis for automobiles and other vehicles, as shown.

In testimony whereof I hereunto affix my signature.

WILLIAM J. P. MOORE.
